UNITED STATES PATENT OFFICE.

HERMAN R. AMELING, OF DECATUR, ILLINOIS.

PROSPECTING-DRILL.

997,358.

Specification of Letters Patent. Patented July 11, 1911.

Application filed February 11, 1910. Serial No. 543,303.

To all whom it may concern:

Be it known that I, HERMAN R. AMELING, a citizen of the United States, and a resident of the city of Decatur, in the county 5 of Macon and State of Illinois, have invented a certain new and useful Improvement in Prospecting-Drills, of which the following is a specification.

This invention relates to prospecting drills 10 and more particularly to core drills of the double-tube type for use in boring through soft rock, coal, clay, etc.

In prospecting, it is desirable, and in many cases an absolute necessity, that the 15 entire core be held intact in order to determine the nature and condition of the layers or strata from which the core is taken. In practice, however, it has been found that the softer material is frequently washed 20 away by the water coming in contact with the core above the cutting portion of the bit. Therefore, in many cases it has been practically impossible to extract a perfect core. In such a case it is difficult to determine the 25 exact nature and condition of the missing portion of the core or the location and thickness of a particular layer or stratum from which the missing portion of the core was taken.

30 My invention has for its principal objects to secure a perfect core; to provide for adjusting and interchanging the cutting bits to suit different conditions; to avoid the disadvantages of the devices heretofore used; 35 and to attain certain other advantages hereinafter more fully appearing.

The invention consists in the parts and in the arrangements and combinations of parts hereinafter described and claimed.

40 In the accompanying drawings which form part of this specification and wherein like symbols refer to like parts wherever they occur, Figure 1 is a longitudinal section through a double-tube core drill embodying my invention and equipped with a chisel-edge core bit; Fig. 2 is a fragmentary section of the cutting portions of the bits as shown in Fig. 1; Fig. 3 is a longitudinal section showing a modified arrangement of the drill; and Fig. 4 is a fragmentary section of the cutting portions of the bits shown in Fig. 3.

Referring now more particularly to Figs. 1 and 2 of the drawings, the device com-

prises an outer tube or barrel 1 which is 55 detachably secured at its upper end to a coupling member 2. The connection between the barrel 1 and coupling 2 may be effected in any desirable manner, but preferably by a screw thread, as shown. The coupling 60 member 2 has a screw-threaded bore 3 which is adapted to receive the end portion of a pipe or tube (not shown) which is attached to the actuating device of the machine and through which water is conducted to the 65 tube 1 in the ordinary manner. An inner tube or core barrel 4 is fitted loosely inside of the tube 1, there being sufficient space between the two tubes to permit free circulation of water therethrough. The upper end 70 portion of the inner tube or barrel 4 is internally screw-threaded and secured to a tubular bushing 5 which is provided with an annular shoulder against which the end 75 of the tube 4 abuts. Swiveled in the bushing 5 is a cylindrical stem 6 which is screw threaded so as to fit in a threaded bore 7 in the coupling member 2. A jam nut 8 is mounted on the stem 6 and adapted to impinge against the end of the coupling 80 member 2 whereby said stem may be locked in adjusted positions lengthwise of said coupling member. The stem member 6 is provided with a collar or annular shoulder 85 9 which rotatably fits the bore of the bushing 5. On opposite sides of the collar 9 are antifriction bearings 10, the upper bearing being retained by an internal annular shoulder 5a at the upper end of the bushing and the lower bearing by a screw-plug 90 11 in the lower end of the bushing. By this arrangement, the tubes 1 and 4 are independently rotatable but held against independent endwise movement except for adjustment. On the lower end of the tube 1 95 is secured an annular bit 12 whose cutting end and circumferential edge portion may be studded with diamonds or crystals in the usual manner. The diameter of the opening at the cutting end portion of the annular bit 12 is less than the bore of said bit, whereby an internal annular shoulder is provided. The bit is notched or slotted as at 13, and said notches or slots extend above the internal annular shoulder, preferably at four diametrical points. However, any desirable number of notches may be provided. As shown in Fig. 1, the lower end 100 105

of the core barrel or tube 4 is externally screw-threaded and it has secured thereon an annular core bit 14. The opening in the lower part of the bit 14 is contracted 5 or of less diameter bore of the inner barrel 4 and the lower portion of the bit is tapered as at 15 to a sharp cutting or chisel-edge. In boring through very soft material, the inner barrel or tube 4 is adjusted with 10 respect to the outer tube or barrel 1 so that the chisel-edge of the bit 14 extends a short distance beyond the end face of the cutting bit 12. In the operation of the drill, the inner barrel 4 by reason of its bit 14 pressing ahead of the bit 12 on the outer tube 1 and owing, also, to the arrangement of the antifriction bearings 10 and swivel stem 6, said inner barrel 4 is held from rotation 15 while the outer tube 1 with the cutting bit 12 thereon is being rotated. The water which is conducted through a chamber 2^a and passageways 2^b in the coupling member 2 and into the upper part of the tube 1, is forced through the space between the two 20 tubes 1 and 4 and passes out through the notches 13 in the bit 12. It is noted that, as the core bit 14 projects ahead of the bit 12, the water will not come in contact with the core which is forced up into the inner 25 tube 4 as the drill progresses. Port openings 16 are provided in the core barrel 4 near the upper end thereof so that the confined air is permitted to escape into the space between the tubes 1 and 4 and thereby 30 prevent the formation of an air cushion on top of the core which would retard the progress of the drill or prevent the core from entering the tube the full length thereof. By adjusting the swivel stem 6 lengthwise 35 40 of the coupling member 2, the cutting edge of the core bit 14 may be adjusted to different positions relative to the cutting end of the outer bit 12, as it is obvious that the chisel edge of the bit 14 may be either flush 45 with the cutting edge of the bit 12 or some distance ahead of the same, depending upon the condition or hardness of the material which is to be drilled.

When boring through hard coal or very 50 hard material, a core bit 17 having a blunt end is substituted for the chisel edge bit 14 on the inner tube 4 as shown in Figs. 3 and 4 of the drawings. This bit 17 is provided with notches 18 in its peripheral edge portion 55 which are arranged to register with the slots 13 in the bit 12. In this case, the bottom faces of the two bits 12 and 17 are set preferably flush with each other and, except where the slots 13 in the bit 12 and 60 notches 18 in the bit 17 respectively register, said bits fit snugly together all around their cutting edges, as more clearly shown in Fig. 4. Preferably, the core bit 17 is reduced in diameter at its lower end so as to fit 65 the contracted opening at the lower end of

the outer bit 12. In this case, also, the antifriction bearings 10 are removed and the collar 9 on the swiveled stem 6 is moved up against the end shoulder 5^a of the bushing 5 and a block or blocks 19 are inserted 70 in the bushing. The blocks 19 are of such thickness or length that the screw-plug 11 will bear against the same when screwed into the bushing and thereby clamp the collar 9 on the swivel stem 6 tightly in the 75 bushing. To guard against the swivel stem turning independently of the bushing 5 should the clamp become loosened, it is preferable to provide holes 20 in the end of the bushing 5 and also provide holes in the collar 9 so as to register with said holes 20 and insert pins 21 therein. By this arrangement, the two tubes 1 and 4 are fixed 80 so as to rotate together.

A rounded annular shoulder 22 is provided on the inner side of the bits 14 and 17 above the contracted openings at the cutting ends thereof on which the bottom edge portion of the core will rest when the drill is withdrawn. To extract the core from the 90 inner tube, the outer and inner tubes are respectively disconnected from the coupling 2 and the bushing 5 is removed from the inner tube or core barrel 4. The core may be then removed from the barrel 4 through the 95 end from which the bushing 5 is removed.

By the construction and arrangement of the device herein set forth the parts can be readily adjusted and interchanged to drill 100 soft and hard materials and the core can be extracted intact notwithstanding that it is taken from layers or strata of material of different character.

Obviously, the device admits of considerable modification without departing from 105 my invention. Therefore, I do not wish to be limited to the exact construction and arrangement shown.

What I claim is:

1. A rotatory core drill comprising an outer 110 barrel having an annular cutting bit on the end thereof and an inner core barrel having an annular bit on the end thereof, the cutting end of said inner bit being extended ahead of the cutting end of said outer bit 115 and said outer and inner barrels being fixed against endwise movement independently of each other.

2. A rotatory core drill comprising an outer tube having an annular cutting bit on the end thereof and a core tube swiveled within said outer tube so as to rotate independently thereof, but being fixed against independent endwise movement, said core tube being of a diameter less than the diameter of the bore of said outer tube and having an annular core bit on its end, the cutting end of said core bit being projected ahead of the cutting end of the bit on said outer tube.

3. A rotatory core drill comprising an outer tube having an annular cutting bit on the end thereof and a core tube swiveled inside of said outer tube and adjustable lengthwise thereof, means for securing said outer and inner tubes in adjusted position lengthwise with respect to each other, said core tube having an annular core bit on its end in coöperative relation to the cutting bit on 10 said outer tube, the annular cutting bit on the outer tube being notched at its cutting edge and said annular bit on the core tube being continuous and imperforate.
4. A rotatory core drill comprising an outer tube and a core tube swiveled inside of said outer tube so as to rotate independently thereof, but being fixed against independent endwise movement, an annular cutting bit secured on the end of said outer tube, said 15 cutting bit having its cutting end slotted, and an annular core bit on the end of said inner core tube, said core bit being continuous and unbroken and projected ahead of the cutting end of said outer bit.
5. A rotatory core drill comprising an outer tube having an annular cutting bit on the end thereof and a core tube swiveled inside of said outer tube and having an annular chisel bit on the end thereof, the cutting 20 edge of said outer bit being notched and the cutting edge of said chisel bit being continuous and projected ahead of the cutting end of said outer bit and said outer and inner tubes being fixed against endwise movement independently of each other.
6. A core drill comprising an outer tube having an annular cutting bit on the end thereof and a core tube swiveled inside of said outer tube and adjustable lengthwise 25 thereof, said core tube having an annular chisel bit on its end in coöperative relation to said outer bit and means for securing said outer and inner tubes in adjusted position lengthwise with respect to each other.
7. A rotatory core drill comprising a coupling member which is adapted to be connected to a water supply pipe, and having a water passageway therein, an outer tube secured to said coupling member, a core 30 barrel inside of said outer tube, said core barrel being of a diameter less than the diameter of the bore of said outer tube, an axial swivel member connecting said core barrel with said coupling member, an annular bit secured on the end of said outer tube and having water outlet openings in 35 its cutting edge portion, and an annular core bit secured on the end of said core barrel in coöperative relation to said first-mentioned bit, said annular core bit having an unbroken inner face, and having notches in the outer face at its cutting edge portion, said notches being arranged and adapted to 40 coöperate with the water outlet openings in the cutting edge portion of said outer bit.
8. A rotatory core drill comprising a coupling member which is adapted to be connected to a water supply pipe and having a water passageway therein, an outer tube secured to said coupling member, a core barrel 45 mounted inside of said outer tube, said core barrel being of a diameter less than the interior of said outer tube, an axial swivel member connecting said coupling member and said core barrel, whereby the latter is permitted to rotate independently of said outer barrel tube, but fixed against independent endwise movement, an annular cutting bit secured on said outer tube, and an annular core bit secured on the end of said 50 core barrel, said core bit being extended ahead of the cutting end of said first mentioned bit and having an unbroken inner face.
9. A rotatory core drill comprising a coupling member which is adapted to be connected to a water supply pipe and having a water passageway therein, an outer tube secured to said coupling member, a core tube 55 inside of said outer tube, said core tube being of a diameter less than the diameter of the bore of said outer tube, an axial member swiveled in said core tube and being adjustable lengthwise with respect to said coupling member whereby said core tube may be adjusted lengthwise with respect to said outer tube, an annular cutting bit mounted on the end of said outer tube, and a core bit mounted on the end of said core tube in coöperative relation to said first mentioned bit.
10. A core drill comprising an outer tube, a core tube mounted within said outer tube, and an interchangeable connection between said outer tube and said core tube whereby the same may be held against independent endwise movement and either held against independent rotation or permitted independent rotation when desirable.
11. A core drill comprising an outer tube, a core tube mounted within said outer tube, said core tube being of a diameter less than the bore of said outer tube, an annular cutting bit mounted on the end of said outer tube, a core bit mounted on the end of said core tube in coöperative relation to said outer bit, and an interchangeable connection between said outer tube and said core tube whereby the same may be held against independent endwise movement and either held against independent rotation or permitted independent rotation when desirable.
12. A core drill comprising an outer tube having an annular cutting bit on the end thereof, a core tube mounted within said outer tube and having an annular core bit on its end in coöperative relation to said outer bit, and an interchangeable and longitudinally adjustable connection between said outer tube and said core tube whereby

the same may be adjusted lengthwise with respect to each other but are held against independent endwise movement after adjustment is effected and whereby, also, they
5 may be either held against independent rotation or permitted independent rotation when desirable.

Signed at St. Louis, Mo., this 7th day of February 1910.

HERMAN R. AMELING.
